UNITED STATES PATENT OFFICE.

OVIDIO ROQUE PODESTÁ, OF BUENOS AIRES, ARGENTINA.

SUPPORTING DEVICE FOR SOCKS AND THE LIKE.

Application filed January 19, 1927, Serial No. 162,119, and in Argentina June 12, 1926

My present invention relates to an improved support for socks and the like, its main object being to provide a support which not only is very efficient in use and avoids the usual pressure exerted on the legs by the garters used heretofore for the same object, but also is entirely invisible.

In order that the invention be clearly understood and easily carried into practice, 10 a preferred embodiment thereof has been shown in the appended drawing wherein—

Fig. 1 is a plan view of the support and Fig. 2 shows said support in use.

The support according to my present invention consists of a rigid flat rectangular frame preferably formed by two flat rods 1 and 2 having at one end a suitable fastening device 3 by which it may be fixed to the upper edge of the sock as shown in Fig. 2.

4 is a resilient flat bar which is capable of sliding within guides 5 and 6 provided on the main frame, said bar 4 having a number of orifices 7 through which a fixed pin 8 on the frame 1-2 may be interchangeably passed, whereby the relative positions of the frame 1-2 and bar 4 may be easily adjusted and fixed. The release of the pin from the orifice in which it happens to be engaged can readily be effected by flexing the bar, due to its resilience, away from the frame by pres-

sure applied against its back through the space between rods 1 and 2.

The bar 4 is preferably covered for a part of its length with a rubber sheath 9.

The attachment and working of my improved support will be easily understood from Fig. 2, but it is to be observed that the device is disposed within the sock between the latter and the skin of the user, so that it is entirely concealed from view. 40

I claim as my invention:

A sock supporter comprising an elongated, rigid rectangular frame embodying a pair of flat rods arranged in spaced, parallel relation, and a plurality of transverse guides connecting the same; a narrow, flexible bar slideable endwise between said rods and beneath said guides and provided with a longitudinal series of orifices; a pin secured to the frame and interchangeably engaging said orifices to retain the bar in adjusted position with relation to said frame, said pin being removed from such engagement by flexing the bar away from the frame by lateral pressure applied directly against its back through the space between the rods; and a fastener attached to the upper end of the frame to engage the edge of the sock. 45 50 55

In testimony whereof I affix my signature.
